UNITED STATES PATENT OFFICE

172,414

AUTOMOBILE

Robert Adell, Detroit, Mich.

Application December 29, 1952, Serial No. 22,912

Term of patent 14 years

(Cl. D14—6)

To all whom it may concern:

Be it known that I, Robert Adell, a citizen of the United States of America, residing in Detroit, county of Wayne, State of Michigan, have invented a new, original, and ornamental Design for an Automobile, of which the following is a specification, reference being had to the accompanying drawing, forming a part thereof.

In the drawing:

Fig. 1 is a perspective view of an automobile embodying my new design.

Fig. 2 is an enlarged fragmentary view showing the full line portion of Fig. 1.

Fig. 3 is an enlarged sectional view thereof taken on line 3—3 of Fig. 2.

The dominant features of my ornamental design reside in the full line portion of the draw-

ings showing the ornamental molding in its relationship to the adjacent contour surfaces of the automobile.

I claim:

The ornamental design for an automobile, substantially as shown and described.
